SELF-SPACING SIDING

Clarence R. Eckert, Englewood, N. J., assignor to
 The Barrett Company, New York, N. Y., a corporation of New Jersey

Application December 12, 1931, Serial No. 580,659

5 Claims. (Cl. 20—5)

This invention relates to wall, roof, or other surface coverings, and more particularly, to flexible shingles designed for covering and protecting roofs, walls, or other surfaces. The term 5 "shingle" is used in the claims in a generic sense and is intended to include siding elements, strip shingles, individual shingles, and other elements utilized for protecting or covering roofs, walls, or other analogous surfaces.

10 One object of this invention is to provide a flexible shingle which may be readily and conveniently applied to an inclined or vertical surface. The shingle is designed so that it may be temporarily or permanently supported in the desired overlapping relation with respect to an underlying element and so that one or both ends do not require support from the workman while nailing the elements. This permits the workman to use both hands in nailing the shingles throughout their application, and consequently, materially shortens the time required to apply the elements in desired overlapping relation and results in more accurate positioning of the elements with respect to each other.

15 Another object is to provide a durable, weatherproof shingle, capable of ready and accurate placement in overlapping courses, of artistic appearance and enhanced architectural value.

20 Other objects and advantages of this shingle will appear from the following detailed description.

25 Heretofore, felt base shingles and siding elements have been provided with aligning guides in the transverse edges to assist in laying the elements in proper relation to each other. In applying an overlying course of elements, the workman held one end with one hand in the desired position while nailing the other end with the other hand. The workman, thus, could use one hand only for the initial nail placed in the shingle and in order to insure proper positioning of the shingles had to ascertain that both ends were properly positioned before nailing one end. Applying strip shingles of considerable overall 30 length in this manner frequently resulted in the improper nailing of the shingles and damage thereto due to securing nailing of one end while the other end was not properly positioned, and then forcing the other end into the desired overlapping relation with consequent impairment of the fibrous base.

35 This invention overcomes the above and other disadvantages of existing shingles and siding elements. In accordance with this invention, the covered or unexposed portion of flexible shingles

designed to be laid in overlapping courses, the individual elements in each course being laid in abutting relationship, are provided, preferably near the transverse edges and spaced from the upper edge, with means for engaging a portion 5 of the underlying element to secure the overlying element in desired overlapping relationship with respect to the underlying element during the nailing of the overlying element. The means may be in the form of an interior slit, slot or projection or a projection and complementary recess on the transverse edges which not only function to properly space elements in contiguous courses but also serve to align contiguous elements in the same course. Hence, the shingle requires no support from the workman and he may use both hands in nailing or otherwise securing it.

40 In the accompanying drawing, forming a part of this specification and showing, for purposes of exemplification, preferred forms of this invention without limiting the claimed invention to such illustrative instances—

Fig. 1 is a plan view of a shingle;

Fig. 2 is a vertical section on an enlarged scale taken in a plane passing through the line 2—2 of Fig. 1;

Fig. 3 is a fragmentary plan view of a number of shingles of the type shown in Fig. 1 arranged in overlapping relationship;

Fig. 4 is a plan view of a modification of the shingle of this invention;

Fig. 5 is a plan view of another modified form of shingle; and

Fig. 6 is a plan view of still a further modified form of shingle.

35 In the preferred embodiment illustrated on the drawing, the invention is shown incorporated in a strip shingle having rectangular tabs disposed along one longitudinal edge thereof and the present description will be confined to the present illustrated embodiment of the invention. It will be understood, however, that the novel features and improvements are susceptible to other applications, such for example as siding and shingle elements without tabs or with tabs of different shapes, or elements not made from a felt base but other flexible base. Hence the scope of this invention is not confined to the embodiment herein described.

40 In the drawing, with particular reference to Figs. 1 and 2, reference numeral 11 indicates a felt base which may be made from rag fiber, paper stock, with or without fillers, as is well known in the roofing art, and then thoroughly saturated and impregnated with waterproofing material,

- such as asphalt or other bituminous compositions. The felt base is coated in known manner on both sides with waterproofing material, such as asphalt, to form the coating layers 12, 13.
- 5 Coating 12 completely covers the face of the element and layer 13 completely covers the rear of the element. A talc or mica dust layer 14 is applied to coating 13 to render the back of the element non-cementitious.
- 10 One longitudinal edge of the body portion 15 is formed with rectangular tab 16 separated by narrow slots 17. The tabs 16 are completely covered with coarse granular material 18 of one color or a blend of colors, the granular material being
- 15 partially embedded in the coating layer 12 therebeneath. The coarse granules completely cover the tabs extending from the lower edge of the elements to a depth equal to that of slots 17. The coarse granules may be crushed rock, slate or other grit employed for surfacing roofings.
- 20 As one example of the mesh characteristics of the coarse granular material suitable for covering the tab portions, the following is given:

	Per cent (approximately)
Retained on the 6 mesh screen	0
Retained on the 8 mesh screen	19
Retained on the 10 mesh screen	67
Retained on the 14 mesh screen	12
30 Retained on the 20 mesh screen	1.5
Retained on the 28 mesh screen	0.5

The body portion 15 is preferably surfaced with granular material 19, such as crushed rock or slate, or other grit, preferably materially finer than the granules 18. Granules 19 may be of a dark color, as blue-black, which is less expensive than the red, yellow, or other light colored granules utilized for surfacing the tab 16. One example of the mesh characteristics of fine granular material suitable for surfacing body portion 15 is as follows:

	Per cent
Retained on a 28 mesh screen	0 to 5
Retained on a 35 mesh screen	20 to 40
Retained on a 48 mesh screen	30 to 50
Retained on a 60 mesh screen	15 to 25
Retained on a 100 mesh screen	3 to 8
Passing through 100 mesh screen	0 to 2

50 It will be noted that the major portion of granules 18 covering the tabs is retained on a 10 mesh screen whereas the major portion of the fine granules 19 covering the body portion passes through a 35 mesh screen. The use of granular material of such extremes in mesh characteristics for surfacing the body portion and the tabs of the elements results in the tab portions having the appearance of substantially greater thickness than the body portion.

In the embodiment of the invention shown in Figs. 1 to 5, transverse edge 21 is straight while the other side edge is formed with what might be considered a rectangular projection 23. This projection is provided by the cutting of slot 24 in the extreme right edge of the element. Contiguous shingles in the same course are laid as shown in Fig. 3 with projection 23 abutting against side 21 of a contiguous element, the lower portions of the contiguous elements defining the slot 25, which is substantially identical with slots 17 in the elements. The overlying elements are placed with the forward edges spaced from the upper edges of the tabs; i. e., the upper edges of 70 the slots defining the tabs. Thus, a narrow strip

26 of fine granular material 19 is exposed between adjacent courses of elements. The fine granular material exposed along strip 26 and between slots 17 and 25 contrasts with the coarse granular material 18 of the tabs. Utilizing blue-black fine granules and red or other brick colored coarse granules for surfacing the body portion and tab portions of the elements, respectively, application of the elements, as shown in Fig. 3, results in the stripes 26 and portions exposed through slots 17 and 25 simulating mortar disposed about the brick appearing portions 18. In other words, the elements when laid as shown in Fig. 3 impart to the observer the appearance of a brick wall.

10 Horizontal interior slits 27 are spaced from the upper edge of the shingles of Figs. 1 and 2, near the transverse edges thereof. These slits serve as guides to indicate the laying position of the overlying element with respect to the underlying element. Further, they permit depression of part of the body portion indicated by the reference numeral 28 to form a ledge 29, which engages the upper edge as indicated at 31 (Fig. 3) of the underlying element. Hence, the overlying 25 shingle is temporarily held in desired position by ledge 29 engaging the upper edge of the underlying element and the roofer is free to use both hands in nailing the overlying element in position.

15 The modification of Fig. 4 differs from that of Fig. 1 chiefly in that instead of having horizontal slits 27 in the body portion 15, the interlocking projections 32 are formed therein. These projections are made by cutting horizontal slits 33 and 35 intersecting the slits 33 by spaced interior vertical slots 34 which define the tongues or projections 32. By flexing tongues 32 so that they extend beyond the back of the shingle, the elements of Fig. 4 may be laid with tongues 32 passing under 40 the upper portion of an underlying element. Thus, the overlying element is held in position on a vertical wall or inclined roof or other surface by the upper edge of tongue 32 resting on the upper edge of the underlying element. As an 45 alternative procedure, the free end of tongue 32 may be caused to rest on the upper edge of the underlying element, which thus holds the underlying element in desired nailing position.

20 If tongue 32 is intended to pass down beneath 50 the upper portion of an underlying element, it is spaced from the lower edge such that when tongue 32 is forced home, the forward edge of the tabs occurs somewhat above the tops of the slots of the underlying elements to define the mortar 55 strips 26. If on the other hand it is desired to have the forward edge of the tongue rest on the upper edge of the underlying element, then the tongues are positioned closer to the upper edge a distance equal to the length of the tongue 32 so 60 that when the tongue of one element rests on the upper edge of an underlying element, the forward edge of the overlying element is positioned somewhat from the tops of the recesses or slots of the underlying element to define the mortar strip 26. 65

The shingle of Fig. 5 differs from that of Fig. 1 in that an interior open recess or slot 37 is utilized instead of the slits 21 of Fig. 1. This construction permits the roofer to insert a knife or other tool through slot 37 and positions the tool behind 70 the upper edge of the underlying element to temporarily support the overlapping elements in desired overlapping relation. After nailing the elements the knife or other tool is withdrawn.

75 In the modification of Fig. 6, side edge 38 is pro-

vided with a recess 39 having a side 41 substantially parallel to the longitudinal axis of the element. A slit 42 extends into the body of the shingle. This slit forms an extension of the line defining side 41 of recess 39.

The other transverse edge of the shingle of Fig. 6 is formed with a projection 43 complementary to recess 39. Slit 44 forms an extension of line 45 defining one side of projection 43. In the laying of the shingle of Fig. 6, contiguous elements in the same course are laid with the projections of one element entering into the recess of a contiguous element. The overlying elements are laid by first flexing either the portion of the element above slit 44 or 42 or both and causing the lower edge of the portions flexed to engage the upper edge of the underlying element. Thus, the overlying element is supported by the underlying shingle and the roofer is free to nail the elements, utilizing both hands. As in the case of the other modifications, the interlocking projections and recesses are so disposed that the forward edges of the element are properly aligned with respect to the underlying elements to obtain a mortar line effect between adjacent courses.

It will be noted that the shingle of this invention does not require support from the roofer during nailing. Further, the supporting slits or projections serve to align the forward edges of the overlying elements with respect to the underlying shingles, and this in a simple and efficient manner. In the case of brick siding elements, as disclosed herein, the projections position adjacent courses so as to obtain the effect of mortar about the brick colored tab portions.

The surfacing of the tab portions with granular material considerably coarser than that applied to the body portion imparts to the tabs an appearance of thickness and rigidity and heightens the brick wall effect since the mortar simulating portions appear to be depressed about the confines of the brick as in actual brick wall construction.

Since different embodiments of the invention could be made without departing from the scope of this invention, it is intended that all matter contained in the above description or shown in the accompanying drawing shall be interpreted as illustrative and not in a limiting sense.

I claim:

1. A flexible shingle arranged to be laid with other like shingles in overlapping courses and having in one transverse edge an aligning recess provided with a slit extending into the body of the shingle and in the opposite transverse edge a complementary projection provided with a slit extending therefrom into the body of the shingle, the projection of one shingle arranged to enter into the recess of a contiguous shingle in the same course to align the elements in the same course, and the portion of the shingle above the slits arranged to be flexed to engage the upper edge of an underlying shingle to temporarily support the same in desired overlapping relation with respect to the underlying shingle.

2. A sliding element arranged to be laid with other like elements in overlapping courses and having rectangular tabs disposed along one longitudinal edge of the body portion thereof, comprising a fibrous base coated on both sides with bituminous material, the tab portions being completely surfaced with coarse brick colored granular material and the body portion being completely surfaced with dark colored fine granular material, one side edge of said element provided

with an aligning recess having one side substantially parallel to the longitudinal axis of the element, and a slit extending from said side into the body portion of the element, the opposite side of the element being formed with a projection complementary to said recess and a slit extending from said projection into the body portion of said element, said slits permitting flexure of the body portion of the element thereabove to engage the upper edge of an underlying element to support the overlying element during the application thereof to a surface in desired overlapping relation with respect to the underlying element.

3. A siding element arranged to be laid with other like elements in overlapping courses and having rectangular tabs along one longitudinal edge of the base portion thereof, said element being provided with an aligning recess in one transverse edge of the body portion, said recess having one side substantially parallel to the longitudinal axis of the element, and a slit extending from said side into the body portion of the element, the other transverse side of the element being provided with a projection complementary to said recess, a slit extending from said projection into the body of said element, said slits permitting flexure of the body portion of the element thereabove to engage the upper edge of the underlying element to support the overlying element during application thereof to a surface in desired overlapping relation with respect to the underlying element.

4. A siding element having brick simulating portions along one longitudinal edge of the body portion and composed of a saturated felt base having on the face intended to be exposed to the weather a single layer of waterproof coating material of substantially uniform thickness and a layer of granular material partially embedded in the said coating layer, the granular material on the brick simulating portions being materially coarser than that on the body portion so that the thickness of the brick simulating portions is substantially greater than that of the body portion, said element adapted to be laid with other like elements in overlapping courses with a portion of the fine granular surfaced body portion of each element exposed to the weather between adjacent courses of the elements so as to produce an appearance of a depressed mortar line above the brick simulating portions, each element having slits located below the upper edge in the body portion thereof, the portions of the elements above the slits being designed to be depressed to engage an upper edge portion of an underlying element and thus support the overlying element in position with respect to the underlying element to expose to view said horizontal mortar line.

5. A siding element having brick simulating portions along one longitudinal edge of the body portion and composed of a saturated felt base having on the face intended to be exposed to the weather a single layer of waterproof coating material of substantially uniform thickness and a layer of granular material partially embedded in the said coating layer, the granular material on the brick simulating portions being materially coarser than that on the body portion so that the thickness of the brick simulating portions is substantially greater than that of the body portion, said element adapted to be laid with other like elements in overlapping courses with a portion of the fine granular surfaced body portion of each element exposed to the weather between adjacent courses of the elements so as to produce an appearance of a depressed mortar line above the brick simulating portions, each element having slits located below the upper edge in the body portion thereof, the portions of the elements above the slits being designed to be depressed to engage an upper edge portion of an underlying element and thus support the overlying element in position with respect to the underlying element to expose to view said horizontal mortar line.

cent courses of the elements so as to produce an appearance of a depressed mortar line above the brick simulating portions, said siding element arranged to be laid with other like elements in overlapping courses and having in the portion intended to be overlapped by an underlying ele-

ment a projection arranged to be flexed to extend back of the element and to engage the upper edge of an underlying element to support the overlying element in desired overlapping relation with respect to the underlying element.

CLARENCE R. ECKERT.
